ADDING MACHINE AND THE LIKE.

Application filed July 3, 1924. Serial No. 724,036.

REISSUED

This invention relates more particularly to the recording function of an adding and listing machine and has special reference to the tabulating equipment of such machine, which equipments usually comprise a laterally shiftable paper carriage with suitable means for controlling the columnar positioning of the same.

The principal object of my present invention is to better adapt the tabulating equipment of an adding and listing machine to the handling of various work sheets such, for example, as ledger sheets, bills, record or proof sheets, and the like. Among other more specific objects of my invention are the provision of means for automatically tilting the platen carrying frame when the paper carriage is moved to a predetermined columnar position, to facilitate the insertion in and removal from the paper carriage of some of the work sheets, while the platen frame is latched in its tilted condition, the employment of means for disabling such tilting device, and the provision of improved means for supporting the work sheet on the paper carriage in the proper or desired printing position and for readily accommodating work sheets of different sizes.

With the above and incidental objects in view the invention consists in certain novel features of construction and combination of parts, the essential elements whereof are recited in the appended claims and a preferred form of embodiment of which is described in detail hereinafter and illustrated in full in the accompanying drawings which form part of this specification.

Of said drawings, Fig. I is a right-hand side elevation of the rear portion of an adding machine, showing my invention applied thereto, parts of the machine proper being broken away, and parts of the carriage mechanism being omitted or shown in section to disclose the essential features of my invention more clearly to view. Fig. II is a rear elevation of the machine with one of the paper tables and some of the work sheets broken away; Fig. III is a top plan view of the carriage equipment with some of the parts broken away and others shown in section; Fig. IV is a detail section taken through the platen carrying frame and the floating paper pan, the section being taken substantially on the line IV—IV of Fig. VII; Fig. V is an irregular vertical section taken through the paper carriage equip-

ment substantially on the line V—V of Fig. II; Fig. VI is another vertical section through the carriage equipment, being taken substantially on the line VI—VI of Fig. II, and showing the platen carrying frame in the tilted back condition; Fig. VII is an enlarged fragmentary view through part of a carriage equipment, the section being taken substantially on the line VII—VII of Fig. IV; Fig. VIII is a fragmentary perspective view of one of the pressure rollers which engage the bill; Fig. VIII^A is a detail perspective view of one of the spring supporting devices for the floating paper pan; Fig. IX is a right-hand side view of part of the carriage equipment, with the line spacing mechanism and other parts omitted and shows the platen frame in its tilted condition; Fig. X is still another vertical section through the carriage equipment, the section being taken substantially on the line X—X of Fig. II; Fig. XI is an enlarged fragmentary section taken substantially on the line XI—XI of Fig. II; Fig. XII is a fragmentary rear view showing the mechanism for tilting the platen frame rearwardly; Fig. XIII is a fragmentary section taken on the line XIII—XIII of Fig. XII with the device for controlling the tilting of the platen frame latched in inactive condition; Fig. XIV is a rear elevation of the mechanism for controlling tabulating movement of the paper carriage by the electric motor from its last to its first columnar position, with the parts shown in normal condition; Fig. XV is a similar view but shows the parts in the positions which they assume when the paper carriage is moved slightly past its last columnar position; Fig. XVI is a rear elevation of part of the mechanism shown in Figs. XIV and XV and shows the elements in the condition which they assume just as the carriage is returned slightly past its first columnar position; Fig. XVII is a perspective view of the clutch control bar and latch; Fig. XVIII is a detailed perspective view of the guide plates and their adjustable devices for supporting the bills and ledger sheets; Fig. XIX is a horizontal section taken substantially on the line XIX—XIX of Fig. XVIII; Fig. XX is a vertical section through part of the platen and a bill supporting device of modified form, the section corresponding to one taken on the line XX—XX of Fig. XVIII; Fig. XXI is a rear view of the adjustable plate and bill supporting shelf shown

110

115

in Fig. XX; Fig. XXII is a detail plan view, foreshortened, of the cam plate for rocking the platen frame, and shows the means for securing it to the square supporting bar; and 5 Fig. XXIII shows examples of the work sheets adapted to be handled by the use of my invention.

The invention herein shown is applied to the well-known Burroughs adding and listing machine, but it is to be understood that it 10 is not limited necessarily in its application thereto. For the sake of illustration and convenience, but without limitation thereto, I have also shown and will describe my invention 15 as being peculiarly adapted to handle the bookkeeping work of different kinds of public utility accounting systems, using, for example, ledger sheets, bills, and proof or record sheets.

20 In view of the fact that the Burroughs machine is in extensive commercial use and its basic principles of operation are well known, it will be wholly unnecessary to describe the machine proper in any detail. The usual 25 numeral keys (not shown) are employed for setting up the various items and controlling the extent of movement of the usual actuating levers which carry type plates 1 for presenting the items and totals to the printing line, 30 racks being carried at the forward ends of the levers for actuating the usual adding and subtracting registers. A back panel 2 of the supporting framework of the machine has secured to it the usual track 3 upon which the 35 laterally shiftable carriage 4 runs. A rotating platen 5 is supported in a rocking frame 6—6^a mounted on a cross-rod 7 carried by the carriage 4. This platen frame 6—6^a also carries a paper support or back 8 (Figs. I, II, 40 III and V) for guiding the proof or record sheet, such as sheet P, shown in Fig. XXIII. Laterally adjustable guides 9 are slidably mounted on the back 8, being provided with lock nuts and bolts 11 with the bolts extending 45 through slots 10 in the back 8, as shown in Rinsche Patent No. 1,208,375, granted December 12, 1916, to which reference may be had with respect to this and certain other well known features of the Burroughs carriage equipment.

50 Also mounted on the paper carriage 4 is a rock shaft 12 (Figs. I and II) carrying the customary series of column stops or dogs 13 for determining the columnar position of the carriage. On each operation of the machine, when the carriage is moved from right to left (as viewed from the front) from one columnar position to the next by the carriage spring 14 (Fig. I), releasing mechanism 15 is 55 operated by a cam 16 through the lever 17 to rock the shaft 12 and thereby move one of the stop dogs 13 out of engagement with a permanent stop 18, the shaft 12 being rocked back to normal position by a spring 19 through a lever 19^a and arm 19^b, so that the

next stop abuts the permanent stop 18 to arrest the carriage in the next columnar position, all of which is the usual construction and operation in Burroughs machines.

The machine is operated by an electric 70 motor 20 through suitable connections, the motor and connections being substantially the same as those disclosed in Patent No. 866,750, issued September 24, 1909, upon an invention 75 of Jesse G. Vincent, to which reference may be had for a more detail description of the same. Suffice it to say here that, when the touch or finger bar of that patent is depressed by the operator, the motor clutch is rendered effective, whereupon the drive shaft is given 80 its positive stroke by the motor through a crank arm 21, a link 22 and an arm 23, the drive shaft being returned to its normal position by the customary power springs 24.

85 As an incident to the operation of the machine, when the carriage is in its last columnar position (i. e., its extreme left-hand position) it is returned toward the right to its first columnar position by the motor 20 through suitable connections such as those 90 shown and described in Rinsche Patent No. 1,580,534, to which reference may be had for a more detailed description of the same. It will be sufficient to but briefly describe this mechanism here. The motor 20 drives a 95 shaft 25 (Fig. I) carried by a vertical housing 26. An irregular shaped housing 27 is secured to the upper end of the housing 26 and a gear (not shown) is secured to the upper end of the shaft 25 which extends into the housing 27. This gear meshes with a gear 28 (Figs. XIV and XV) journaled on a stud 29 suitably supported in the housing 27. On the upper end of the stud 29 is journaled a gear 31 meshing with a rack bar 32 100 (Figs. III, XIV and XV) on the paper carriage 4. Upon normal operation of the machine when the carriage is shifted from right to left, as viewed from the front of the machine, by the carriage spring 14, the rack 32 105 being moved with the carriage rotates the gear 31 which is normally disconnected from the gear 28; but when the machine is operated with the carriage in the last columnar position, the gears 28 and 31 are automatically 110 coupled together by a clutch mechanism, designated generally by the reference numeral 31^a, whereupon the gear 31 is rotated in the reverse direction by the electric motor to return the carriage to the first columnar 115 position in opposition to its carriage spring 14. The clutch device 31^a and its operating lever 39 are the same as that disclosed in the aforesaid Patent No. 1,580,534 and it will be unnecessary to describe them in detail here. The connections for operating the clutch lever 39 have been somewhat modified as will now be pointed out. A stop 33 is adjustably mounted on the carriage rack 32 and is provided at its left-hand end (right-hand end 120

as viewed in Figs. XIV and XV) with a vertical extension which is adapted to engage one end of a sliding bar 34, as the carriage moves slightly toward the left (as viewed from the front) past its last columnar position upon operation of the machine with the carriage in such position, and the bar 34 is thus slid from the position shown in Fig. XIV to that shown in Fig. XV. The bar 34 is guided in its sliding movements by studs 41 and 44 on a plate 43 engaging in slots 42 and 45 in the bar 34. Due to its irregular shape, the bar 34 extends over the supporting plate 43 so that portions of the bar are on opposite sides of the plate 43. An offset downward projection 46 on the bar 34 extends over and in front of the plate 43 to assist in guiding the bar 34 in its sliding movements. A latch 35 is pivotally mounted at 35° on the bar 34 at a point above the slot 45, and the latch 35 is normally held in the position shown in Fig. XIV by a stud 36 against the tension of a spring 37 connected at its ends to the bar 34 and latch 35. In this normal condition of the parts, the clutch lever 39 is held in its clutch disabling position by a stud 40 which engages the upper of two notches 51 in the clutch lever, the stud 40 being carried by a latch arm 50, held in latching position by its spring 52. As the carriage moves slightly past its last columnar position, the stop 33 slides the lever 34 to the position shown in Fig. XV, as above stated, whereupon the latch 35 is raised by its spring 37 when a notch 35a in the latch comes under the stud 36. This rocking movement of the latch 35 results in an upper edge 35b of its extension engaging a stud 38 on the clutch lever 39, thereby rocking the lever 39 to throw in the clutch 31a and cause the gear 31 to rotate with the gear 28 and thereby move the carriage toward the right (as viewed from the front) to its first columnar position. In Fig. XV, the stud 38 is shown slightly above the edge 35b but this is due to the fact that the stud 40 seats itself in the lower notch 51 of the latch arm 50 and raises the one end of the lever 39 a little further than it is raised by the latch 35.

When the carriage is moved by the electric motor from its last columnar position toward the right, as viewed from the front of the machine, the carriage is moved slightly past the first columnar position and during this additional movement the clutch 31a is disabled by the following described mechanism, to permit the carriage to be moved slightly back to its first columnar position by its spring 14. As best shown in Fig. XVI, a clutch releasing finger 204, having a cam face 205, is adjustably mounted on the left-hand end (as viewed from the front) of the rack bar 32. This finger has an offset extension 208 in line with an extension 35d on the latch 35. When the carriage moves slightly past

its first columnar position, as above stated, the offset 208 engages the extension 35d thereby first rocking the latch 35 about its pivot 35c to carry the notch 35a in the latch away from the stud 36 and the edge 35b away from the stud 38 and then slide the bar 34 to normal position. During this sliding movement of the bar 34, the cam edge 205 of the finger 204 engages over a roller stud 206 on the clutch lever 39, thereby rocking this lever from the position shown in Fig. XV to that shown in Fig. XIV to release the clutch 31a and hence disconnect the gear 31 from the gear 28, whereupon the carriage spring 14 moves the carriage slightly back toward the left to its first columnar position. The clutch lever 39 is then retained in its normal position by engagement of the stud 40 on the latch 50 in the upper notch 51 on the clutch lever. In machines to which my invention is preferably applied, the performance of the machine with respect to the registering and recording functions, when the paper carriage is in its different columnar positions, is determined by elements on the paper carriage through suitable connections such as fully shown and described in the Muller Patent No. 1,379,774, granted November 22, 1921. As this mechanism is not essential to the understanding of my invention it is not shown or described in the present drawings and specification. Suffice it to say here that control rollers R (Fig. I) are carried by the carriage and operate control levers A which in turn control the various operations of the recording and registering mechanisms, in order that the machine will properly function in its various columnar positions to perform the class of work for which it is intended.

Examples of work.

Before proceeding to describe the features of the machine constituting my invention, it may be well to describe briefly the operation of the machine in connection with the printing on work sheets, such as shown in Fig. XXIII for illustrative purposes. When the ledger sheet L, the bill B and the proof sheet P and its carbon C, are inserted in the paper carriage, as will be described later, the paper carriage is in its second columnar position and at this time the platen carrying frame is tilted back to facilitate the insertion of the ledger sheet and the bill. For convenience the columnar positions of the carriage will be considered as being numbered from right to left, the extreme right-hand position being treated as the first columnar position. No entry is to be recorded on the ledger sheet L while the carriage is in its second columnar position so that the machine is operated after the platen frame is rocked back to normal position, to permit the carriage spring 14 to move the carriage to the third columnar posi-

tion. In carrying out the present example, the operator now sets up on the keyboard the prior reading "111," the present reading "222," and the consumption "111" cu. ft., it being understood that the machine is "split" so as to avoid one number running into the other, or in other words in order to separate the numbers. Upon operation of the machine the present reading "222" and consumption 10 "111" will be printed on the ledger sheet, but the previous reading "111" will not be printed because of it being hammer blocked, it being preferred not to print this previous reading as it already appears as a previous item in 15 the column above the recorded present reading. The carriage then automatically shifts to its fourth columnar position and the printing mechanism is controlled by one of the rollers R and the machine is again automatically 20 operated to print the three items "111," "222" and "111," on the bill B while the carriage is in the fourth columnar position. These same items are printed on the proof sheet P through the carbon C. The carriage 25 automatically shifts to the fifth columnar position and then the operator sets up the customer's folio number and operates the machine to print this folio number in the "code" column on the proof sheet through the bill 30 and carbon, but this folio number will not be decipherable on the bill as it is printed on a heavy black imprint block d on the bill. The carriage now automatically shifts to the sixth columnar position and the operator set 35 up the monetary items, for example, \$5.00, \$4.00 and \$9.00 and depresses the touch bar to operate the machine. These items are printed on the bill and also on the proof sheet, through the carbon, and a repeat print device, coming into play, through the operation 40 of one of the rollers R, will automatically cause the carriage to shift to the seventh columnar position and effect operation of the machine to repeat print all three items, \$5.00, \$4.00 and \$9.00 on the stub of the bill, but as 45 there is no carbon back of the stub the items will not be printed on the proof sheet while the carriage is in such position. At the end of this operation, as above described, the carriage moves slightly past its seventh columnar position and is automatically returned to its first columnar position by the electric motor. The repeat print device, as 50 controlled by one of the rollers R, again comes into play so that after the carriage has moved to its first columnar position the machine is again automatically operated and the items \$5.00, \$4.00 and \$9.00 will be again reprinted, this time on the ledger sheet, and the 55 carriage will tabulate to the second columnar position, which is shown in Fig. II. It will be observed that the first columnar position of the carriage is really the one in which the last printing operation is performed to complete the entire entry of the transaction. 60

Platen frame tilting device.

The mechanism for tilting the platen carriage when the carriage is in its second columnar position is one of the features of my present invention and will now be described, reference being had more particularly to Figs. V, VI, IX, X, XII and XXII. The side plates 6 and 6^a of the platen frame are braced by a square cross-rod 53, as is usual in the Burroughs machine. Secured to this cross-rod is a tilting cam plate 54 so positioned that when the carriage is moved from its first to its second columnar position, the plate will ride under a roller stud 64, normally in its path, with the result that the platen frame is tilted rearwardly from the position shown in Fig. V to that shown in Figs. VI and IX, in order that both the bill B (Fig. VI) and the ledger sheet L (Fig. X) 80 may be readily dropped into position in front of the platen without interference from the platen or the necessity of feeding them into position by means of pressure rolls. Near the end of the movement of the paper carriage 90 from its first columnar position to its second, the cam plate 54 moves out of engagement with the roller stud 64 but the platen frame is then latched in its tilted position by means of a latch 105 (Fig. IX) as will be described 95 later. The cam plate 54 has supporting end pieces 55 and 56 (Figs. X and XXII) having square recesses to embrace partially the square rod 53 and in order to retain the cam plate in its predetermined position on the 100 rod 53 locking washers 57 are provided. The washers are provided with threaded holes to receive screws 58 (Fig. XXII) extending through the end pieces 55 and 56 and are also provided with square notches having their 105 opposite sides beveled reversely as indicated at 55^a so that they may be readily inserted over the bar 53 angularly, as illustrated by the dash-dot lines in Fig. XXII, and then straightened and moved against the side 110 plates 55 and 56 to which they are secured by the screws 58, the sharp edges, formed by the beveled sides then binding on the square rod 53 sufficiently to prevent longitudinal displacement of the cam plate 54. It will be obvious that when the bolts or screws 58 are loosened, to permit tilting of the washers 57, the cam plate 54 may be slid to any position on the rod 53 so that the platen frame will be rocked rearwardly upon movement of the 115 paper carriage to the selected columnar position, determined by the character of the work to be performed.

The roller stud 64, for tilting the platen frame by its coaction with the cam plate 54, 120 is mounted on the free end of an arm 61 (Figs. XII and XIII) and is held in place thereon by a shouldered nut 65 the reduced portion of which is free to move in an arcuate slot 66 formed in a plate 59 supported on the back 125

plate 43 by bolts 41 and 60 (Fig. XV), the plate 59 being spaced from the plate 43 by suitable spacing collars 59^a. The swinging arm 61 is pivotally supported in a bushing 62 (Fig. XIII) on the plate 59 and is held from displacement by a headed screw 63. The roller stud 64 and its arm 61 are normally held in their upper active position by a spring 67 (Fig. XIII) connected at its ends to an extension of the arm 61 and the plate 59. It will be observed that when the paper carriage is moved from its last columnar position to its first columnar position, by the electric motor, as above described, the lower side of the cam plate 54 engages the roller stud 64, thereupon depressing the roller stud and arm 61 in opposition to the spring 67, the stud and arm being restored to normal position by the spring as the plate 54 passes out of engagement with the roller stud. If it is not desired to tilt the carriage when the carriage is moved from its first to its second (or any other) columnar position, the arm 61 with its roller stud may be swung down to the position shown in Fig. XIII and indicated by the dash-dot lines in Fig. XIII, in which position it will be held by a spring detent 68 which is pivoted at 69 to the plate 59 and has at its free end a stud 70 projecting through a hole in the plate 59 and yieldingly engaging into a depression 59^b of the plate 59.

Paper guide chutes.

In addition to the paper table 8, for supporting the proof sheet P and its carbon as above stated, the paper carriage 4 is provided with another paper guide or plate 71 (Figs. III, V, VI, XI and X) which extends above the platen and has its lower portion curved to extend partially around the front of the platen. This guide plate is provided at its ends with rearwardly extending lugs 74 (Fig. IX) which are connected by screws or otherwise to the side plates 72 and 73 rigidly secured by screws 74^a to the carriage 4. A cross-rod 75 is supported in rearwardly extending lugs 72^a and 73^a (Figs. IX and X) on the side plates 72 and 73, and mounted on this rod is a paper guide finger 76 (Figs. III and V) which acts to guide the bill toward the front of the platen. This guide finger is supported on the cross-shaft 75 by rearwardly extending lugs 76^a and 76^b, and is held against longitudinal displacement by a friction spring 77 and against rotational movement by a spline on the rod 75. Also mounted on the cross rod 75 near its opposite ends are paper guides or chutes 78 and 79 (Figs. III and V) which are also prevented from moving longitudinally by springs similar to the spring 77. These paper chutes 78 and 79, as shown in Figs. III and X, are open at their inner sides and are flaring at the top and somewhat contracted at the bottom. The front walls of the chutes 78 and 79 are

straight and rest against the front plate 71 while the lower portions of the rear walls are inclined forwardly to aid in directing the bill and ledger sheet toward the front of the platen while the platen frame is in its tilted back condition.

Supported on and near the middle of the front plate 71 are two other guide chutes 80 and 81 (Figs. II, III and V) constructed similarly to the chutes 78 and 79, except that the rear walls 80^a and 81^a of the former are much closer to the front walls than is the case in chutes 78 and 79. The guide chutes 80 and 81 are supported on the front plate 71 by means of bolts 82 which extend through elongated slots 84 and 85 (Fig. III) in the front plate 71, thereby permitting adjustment of these chutes 80 and 81 to accommodate work sheets of different widths. As illustrated in Figs. II and III, the bill B has its ends inserted in the chutes 78 and 80 and the ledger sheet L has its ends inserted in the chutes 79 and 81.

In some cases the bill may be somewhat longer than the available distance between the chutes 78 and 80, as when an exceedingly long advertising stub is attached to the bill, in which case one end of the bill is inserted in the chute 78 and the other end, instead of entering the chute 80, will be inserted back of this chute and part of the ledger sheet, and as no carbon is used with the ledger sheet, the printing on the overlapping portion of the latter will not appear on the advertising end of the bill.

100

Pressure rollers and paper pan for proof sheet.

The proof sheet P and the carbon paper (Figs. V, VI, X, and XI) through which the items are printed on the proof sheet, are placed on the table 8 and are guided by the pre-set paper guides 9, when they are fed around the platen upon rotation of the latter and by coaction with pressure rollers 90, the forward end of the proof sheet and carbon being guided by a floating pan 92 and well known guide fingers 91, supported at their upper ends on a cross-rod 91^a and having their forward lower edges offset to slightly overlap the upper front edge of the floating pan 92.

As shown in Fig. VII, each pressure roller 90 is supported on a pair of arms 93 which are notched to fit a shaft 94 and which have the customary extensions 95 engaging flattened portions of the pressure roll control shaft 7. Immediately adjacent and inside of each side arm 93 is another arm 96 also notched to fit the shaft 94. The pressure rolls 90 are yieldingly pressed against the platen by means of springs 97 which encircle the shaft 94, and have their forward ends engaging in holes in projections 96^a on the arms 96 and their other ends underlying

105

110

115

120

125

130

contracted shouldered portions of the pressure roll supporting arms 93. When the shaft 7 is rocked by the device, common to Burroughs machines and not shown in the present drawings, the flattened portions of the shaft 7 separate the two rearward extensions of the arms 95 and 96 thereby relieving the pressure of the pressure rolls from the proof sheet and carbon to permit them to be moved readily to the desired position or withdrawn without the necessity of rotating the platen.

The curved floating pan 92 is substantially the width of the platen and its upper rear corners rest against offset lugs 98 on the side braces 99 which support the paper table 8 at either side and which themselves are securely fastened to the square cross shaft 53 by offset lugs and screws 100, as best shown in Fig. VII. In order to yieldingly support the floating pan 92 and retain it against longitudinal displacement beneath the platen, the pan on its under-side has securely attached thereto two inverted L-shaped brackets 101 (Figs. IV, VII and VIII^A) whose downwardly extending projections are slotted to engage annular recesses 102 in the cross-rod 94. Riveted to the horizontal parts of the brackets 101 are leaf springs 103 whose free ends seat on the offset lugs 96^a (Fig. IV) of the pressure roll engaging members 96, the springs being bent downwardly towards their free ends to such an extent as to create a tendency to force the floating pan against the platen. At each end of the floating pan 92 leaf springs 104 (Fig. IV), similar to the springs 103, are securely fastened and the free ends of these springs likewise engage offset lugs 96 to assist in holding the floating pan in yielding contact with the platen. When the shaft 7 is rocked to move the rollers 90 out of engagement with the platen 5, the forward ends of the levers 96 are lowered thus relieving the tension of the springs 103 and 104. This manner of mounting the pan affords expeditious insertion of the proof sheet and carbon and prevents the carbon from buckling or bending as is very often the case in the usual form of floating pan without the yielding supporting means.

Latch for platen frame.

As stated above, when the paper carriage is in its second columnar position, the platen frame is latched in its rearwardly tilted position by the latch 105 as shown in Fig. IX. This latch is pivoted at 106 to the side plate 72 and its vertical arm, carrying the operating finger-piece 109, is provided with a slot 107 through which a shouldered stud 108 projects, the stud serving as a limit stop for the forward or releasing movement of the latch. The rear end of the horizontal arm of the latch has a notched shoulder 110 which,

when the platen frame is tilted back, as above described, engages a shouldered stud 110^a on the right side plate 6 of the platen frame and is retained in said latching condition by a spring 111. It will thus be seen that when the platen frame is locked in its tilted position, shown in Fig. IX, the latch may be operated by the finger-piece 109 to move the shoulder 110 away from the stud 110^a, whereupon the spring 112 (Fig. II) common to Burroughs machines, will rock the platen frame forwardly to its normal position, in which the platen presses the bill and ledger sheet against the lower curved portion of the paper guide 71. In order to prevent the platen frame from rocking forwardly to its normal position with a jar when the latch 105 is released, a brake lever 113, mounted on the pivot 106, is provided. The under edge of the rearwardly extending arm of the lever 113 is so positioned with respect to the shouldered stud 110^a, that when the platen frame is rocked forwardly upon release from the latch 105, the stud 110^a engages this lower edge thereby rocking the lever 113 counter-clockwise from the position shown in Fig. IX to that shown in Fig. I, against the action of a spring 114 connected to the downwardly extending arm of the brake lever. The clockwise movement of the lever 113, when the platen frame is tilted rearwardly, is limited by engagement of a stud 115 on its downwardly extending arm against the side plate 72. In case the spring 111 fails for any reason to move the latch 105 to latching condition when the platen frame is rocked rearwardly, an offset lip 113^a on the brake lever 113 and projecting over the top of the latch 105, will lower the latch to latching condition, when the spring 114 rocks the brake lever 113 to the position shown in Fig. IX.

Bill and ledger sheet pressure rollers and support therefor.

When the bill and ledger sheet are inserted into the machine, with the platen frame in its tilted condition, the lower edges of the bill and ledger sheet are dropped onto adjustable stops or shelves (to be described presently), which have been pre-set so that the items will be printed on the desired horizontal printing lines on the bill and ledger. These supporting devices are carried by a plate or table 117 (Figs. V, VI, X, XI and XVIII) which is secured by screws 118 to the paper carriage 4 and which extends substantially tangential to the platen and is so positioned that it forms, in effect, a continuation of the front guide plate 71. As shown in Fig. 18, the upper corners of the plate 117 are provided with rearwardly extending lugs or ears 119 secured to the side plates 72 and 73 by screws or otherwise.

Equally spaced along the upper edge of

the paper table or plate 117 are five spring-pressed pressure rollers 120 which, as shown in Fig. VIII, are mounted in hinged brackets 121 the lower parts of which are riveted to the plate 117. Springs 122, having portions encircling the hinge pins, serve to hold the rollers 121 against the platen.

Supporting and collating mechanism for bills.

As best shown in Figs. XVIII and XIX, the plate 117 has parallel guide slots 123 through two of which extend studs 125 having coiled pressure springs which serve to yieldingly retain a plate 124, through which the studs project, in adjusted position on the plate 117. A finger-piece 126 is slidably secured to the plate 124 and forms a finger-hold whereby the plate 124 may be moved up or down to the desired position. The finger piece 126 is provided with screws 124^a (Fig. 5) and flanged nuts 124^b which extend through slots 123^a in the plate 117 to permit adjustment of the plate 124, the carriage being provided with a groove 128^a to accommodate the nut 124^b. Secured to the plate 124 in line with the slots 123 are spring shelves or finger supports 127 in the form of U-shaped leaf springs which act as supports for the lower edge of the bill. The free ends of these spring supports are normally positioned in the slots 123, as shown in Fig. VI, but when the plate 124 is moved near its upper limit of movement, so that the lower part of the bill will be printed on, the spring supports 127 strike the floating pan 92 bending the spring supports forwardly so that their free ends project beyond the slot, as shown in Fig. XI; thus preventing injury to the supports. The carriage 4 is slotted or grooved at 128 in line with these fingers to permit this movement of the finger supports. These grooves 128 also accommodate the heads on the lower ends of the spring-pressed bolts 125. In order to retain the plate 124 in any of its set positions, series of depressions 136 are formed in the plate 117 and the plate 124 is provided with punched projections 137 adapted to engage in the depressions 136.

A modified form of bill support is shown in Figs. XX and XXI. It preferably consists of hinged plates 149 suitably arranged along the top edge of the plate 124 and pressed upwardly in the direction of the platen by suitable springs 150, having portions coiled about the hinge pins for the plates. The hinge eyes of the plates 149 are provided with cut-out shoulders 149^a adapted to engage projections on the upper edge of the plate 124 in order to limit the upward movement of the plates 149.

Supporting and collating mechanism for ledger sheets.

As the ledger sheets are quite long, an auxiliary guide plate 129 (Figs. XVIII and

XIX) is mounted on the plate 117 for guiding the lower portion of the ledger sheet and for carrying an adjustable device 133 which supports the ledger sheet at the desired printing line. This auxiliary guide plate 129 is connected to the plate 117 by bolts and nuts 130, and the bolts extend through a horizontal slot 131 in the plate 117 to permit longitudinal adjustment of the auxiliary guide plate 129 so that the ledger sheet will be centrally supported on a supporting device 133 carried by this auxiliary plate. Two vertical slots 132 having beveled edges, are provided in the plate 129. The ledger sheet support 133 is provided with spring-pressed bolts 134, having conical heads 135 (Fig. X) which engage the beveled sides of the slots and do not project beyond the plate 129 thereby permitting the support 133 to be moved above the lower edge of the plate 117, which movement would be prevented, due to engagement of the projecting heads of the bolts against the lower edge of the plate 117 if the heads projected beyond the plate. The ledger sheet support 133 comprises the two end plates 138 and the integral connecting piece. Each end plate 138 has projections 139 and 140 extending forwardly into the slots 132 to aid in guiding the support during its adjusting movements. The upper ends of the plates 138 are bent rearwardly to form supporting shelves or fingers 144 for the ledger sheet. The slide plates 138 are also provided with punched projections 142 adapted to engage in recesses 141 along each side of the plate 129 to retain and align the ledger sheet support 133 in its adjusted or set position. Finger-pieces 143 project from the connecting portion of the support 133 by means of which the operator moves the support to the desired position. The depressions 136 for the bill support and the depressions 141 for the ledger support are so spaced that for single-space work the supports 124 and 133 may be adjusted a distance equivalent to two depressions for each single space on the bill or ledger sheet.

In order to guide the ledger sheet onto the supporting device 133, a guide plate or strip 145 is secured at its lower end to the lower end of the auxiliary guide plate 129, the guide strip 145 being suitably spaced from the plate 129 and parallel therewith in order to guide the lower edges of the ledger sheets onto the support and also prevent displacement therefrom. Another guide plate 146 is secured near the upper end of the guide strip 145 and it is provided with hooks 147 which engage over the shaft 7.

In case the form of bill used is exceptionally long, as where an exceedingly long advertising stub is attached, so that the stub would extend as far as the guide 146, these long bills would be inserted into the machine by dropping one end into the chute 78 and 901

the central portion back of the chutes 80 and 81 and the other end into the space 148 between the guide plates 145 and 146.

Resumé.

5 It will now be obvious that when the carriage is in its second columnar position, the platen frame is latched in its tilted position by the latch 105 to permit ready insertion of 10 the bill and ledger. The bill is inserted in its guide chutes 78 and 80 and is directed by the plate or table 117 so that its lower edge strikes the supporting fingers 127 which have been adjusted so that the printing will be done 15 on the desired line. The ledger sheet is inserted between its paper chutes 79 and 81 and its lower edge is guided by the auxiliary table 129 and the guide strip 145 onto the supporting device 133 which has also been adjusted 20 to the desired position. The proof sheet and carbon are placed on the table 8 and the platen rotated manually in the usual manner. The latch 105 is then released to permit the platen frame to move back to its normal position, whereupon the machine is ready for 25 the cycle of operations to print the various entries on the various work sheets. As the carriage finally shifts from its first columnar position to its second, the platen frame is tilted back by the cam plate 54 and is then latched in such condition by the latch 105 to 30 permit easy removal of the work sheets while the carriage is in its second columnar position.

35 I claim:

1. In a machine of the class described, the combination with a printing mechanism, of a laterally shiftable paper carriage, a rockable platen carrying frame thereon, means controlling the columnar positioning of said carriage, and means for automatically rocking said platen carrying frame away from the printing mechanism upon movement of the carriage to a predetermined columnar position to permit ready insertion of the work between the platen and the printing mechanism.

2. In a machine of the class described, the combination with a printing mechanism, of a laterally shiftable paper carriage, a platen carried by said carriage and adapted to be moved toward and away from said printing mechanism, means controlling the columnar positioning of said carriage, and means for automatically moving said platen away from said printing mechanism upon movement of said carriage to one columnar position to permit ready insertion of the work to printing position.

60 3. In a machine of the class described, the combination with a printing mechanism, of a laterally shiftable paper carriage, a platen carried by said carriage and adapted to be moved toward and away from said printing mechanism, means controlling the columnar

positioning of said carriage, and adjustable means for automatically moving said carriage away from said printing mechanism upon movement of the carriage to the selected columnar position to permit ready insertion 70 of the work to the printing position.

4. In a machine of the class described, the combination with a printing mechanism, of a laterally shiftable paper carriage, a rockable platen carrying frame thereon, means 75 controlling the columnar positioning of said carriage, and adjustable means for automatically rocking said platen-carrying frame upon movement of the carriage to the selected columnar position to permit ready insertion 80 of the work to printing position.

5. In a machine of the class described, the combination with a printing mechanism, of a laterally shiftable paper carriage, a platen carrying frame thereon, means controlling 85 the columnar positioning of said carriage, and a cam element and an operating element therefor one of which is on said carrying frame for automatically operating said carrying frame upon movement of the carriage to one 90 columnar position.

6. In a machine of the class described, the combination with a printing mechanism, of a laterally shiftable paper carriage, a rockable platen carrying frame thereon, means controlling 95 the columnar positioning of said carriage, a cam element and an operating element therefor one of which is on said carrying frame for automatically rocking the latter upon movement of the carriage to the selected columnar position, and means permitting adjustment of one of said elements to effect such rocking movement of the carrying frame in the desired columnar position of the carriage.

7. In a machine of the class described, the combination with a printing mechanism, of a laterally shiftable paper carriage, a platen carried by said carriage and adapted to be moved toward and away from said printing 110 mechanism, means controlling the columnar positioning of said carriage, means for automatically moving said platen away from said printing mechanism upon movement of the carriage to one columnar position to permit 115 ready insertion of the work to printing position, and means for disabling said last mentioned means.

8. In a machine of the class described, the combination with a printing mechanism, of a laterally shiftable paper carriage, a rockable platen carrying frame on said carriage, means controlling the columnar positioning of said carriage, a cam element and an operating element one of which is on said platen frame 120 for automatically rocking said carrying frame upon movement of the carriage to one columnar position, and means for disabling said elements.

9. In a machine of the class described, the 125

combination with a printing mechanism, of a laterally shiftable paper carriage, a rockable platen carrying frame thereon, means controlling the columnar positioning of said carriage, a cam plate on said platen carrying frame, and an arm carrying a projection which rides over said cam plate to rock said platen carrying frame when the carriage moves in one direction to one columnar position and which rides under said plate upon movement of the carriage in the opposite direction.

10. In a machine of the class described, the combination with a printing mechanism, of a laterally shiftable paper carriage, a rockable platen carrying frame thereon, means controlling the columnar positioning of said carriage, a cam plate on said platen carrying frame, an arm carrying a projection which rides over said cam plate to rock said platen carrying frame when the carriage moves in one direction to one columnar position and which rides under said plate upon movement of the carriage in the opposite direction, and means for disabling said arm.

11. In a machine of the class described, the combination with a printing mechanism, of a laterally shiftable paper carriage, a rockable platen carrying frame thereon, means controlling the columnar positioning of said carriage, means for automatically rocking said platen carrying frame away from said printing mechanism upon movement of the carriage to one columnar position, and means for latching said frame in its rocked position to permit ready insertion of the work to printing position.

12. In a machine of the class described, the combination with a printing mechanism, of a laterally shiftable paper carriage, a platen carried by said carriage and adapted to be moved toward and away from said printing mechanism, means controlling the columnar positioning of said carriage, means for automatically moving said platen away from said printing mechanism upon movement of the carriage to one columnar position, and a latch for holding said platen away from said printing mechanism while said carriage was in such columnar position.

13. In a machine of the class described, the combination with a printing mechanism, of a laterally shiftable paper carriage, a platen carrying frame thereon, means controlling the columnar positioning of said carriage, a cam element and an operating element one of which is on said frame for automatically operating said carrying frame upon movement of the carriage to one columnar position, and a latch for holding said platen carrying frame in its operated position while the carriage is in such columnar position.

14. In a machine of the class described, the combination with a printing mechanism, of

a laterally shiftable paper carriage, a rockable platen carrying frame thereon, means controlling the columnar positioning of said carriage, a cam plate on said frame, an arm carrying a projection which rides over said cam plate to rock said frame when the carriage is moving in one direction from one columnar position to another and which rides under said plate upon movement of the carriage in the opposite direction, and a latch for latching said platen carrying frame in its rocked position while said carriage is in said "another" position.

15. In a machine of the class described, the combination with a printing mechanism, of a laterally shiftable paper carriage, a platen frame on said carriage, a rod on said platen frame, devices for controlling the columnar positioning of said carriage, and means for moving said platen frame to carry the platen away from the printing mechanism when the carriage moves to one columnar position and comprising a cam plate having recesses engaging said rod and pieces secured to said cam plate and also having recesses which engage said rod and are provided with beveled edges binding on said rod.

16. In a machine of the class described, the combination with a printing mechanism, of a laterally shiftable paper carriage, a work sheet guide thereon, a frame pivoted on said carriage, means controlling the columnar positioning of said carriage, a platen carried by said frame and adapted to press the work sheet against said guide, means for automatically rocking said frame to move the platen away from the guide upon movement of the carriage to one columnar position, supporting devices mounted on said carriage and upon which the lower edge of the work sheet rests when inserted between the platen and printing mechanism, and means permitting vertical adjustment of said supporting devices to line space the work sheet.

17. In a machine of the class described, the combination with a printing mechanism, of a laterally shiftable paper carriage, a work sheet guide thereon, a frame pivoted on said carriage, means controlling the columnar positioning of said carriage, a platen carried by said frame and adapted to press the work sheet against said guide, means for automatically rocking said frame to move the platen away from the guide upon movement of the carriage to one columnar position, supporting devices mounted on said carriage and upon which the lower edge of the work sheet rests when inserted between the platen and printing mechanism, means permitting vertical adjustment of said supporting devices to line space the work sheet, and pressure rolls cooperating with said platen to line space the work sheet when the platen is rotated for that purpose.

18. The combination in an accounting ma-

chine having a printing mechanism of a laterally shiftable paper carriage, a rockable platen carrying frame thereon, means for controlling the columnar positioning of said carriage, means for automatically rocking said platen carrying frame away from the printing mechanism as the carriage moves from one columnar position to another predetermined columnar position, means for latching the frame in the position to which it is moved, said automatic moving means having provisions for permitting the release of the frame when the carriage is in the predetermined columnar position, and means for releasing the latching means.

19. The combination in an accounting machine having a printing mechanism of a laterally shiftable paper carriage, means for controlling the columnar positioning of said carriage, a rockable platen carrying frame, means for automatically rocking said frame away from the printing mechanism upon movement of the carriage to a predetermined columnar position, means for latching said frame in said position, and cushioning means for cushioning the movement of the frame towards the printing mechanism when the frame is returned to printing position.

20. The combination in an accounting machine having a printing mechanism of a laterally shiftable paper carriage, means for

controlling the columnar positioning of said carriage, a rockable platen carrying frame normally urged toward said printing mechanism, means for automatically rocking said frame away from the printing mechanism upon movement of the carriage to a predetermined columnar position, means for releasably latching said frame in said position, and means for cushioning the movement of the frame toward the printing mechanism when said latch is released, said cushioning means having connections for moving the latching means to latched position when the frame is rocked away from the printing mechanism.

21. The combination in an accounting machine having a printing mechanism of a laterally shiftable paper carriage for holding work sheets in position to be acted upon by said printing mechanism, means for tabulating said carriage to different columnar positions, said carriage having feed rollers and a platen movable into engagement with the rollers to hold work sheets in printing position and movable out of engagement to permit work sheets to be placed in and removed from printing position, and means controlled by the carriage and acting automatically as the carriage is moved to predetermined columnar positions to move said platen.

ARTHUR S. TREW.
